(57) **CLAIM**

I claim the ornamental design for a self contained plant growing apparatus, as shown and described.

DESCRIPTION

FIG. 1 is a perspective exploded view of a self contained plant growing apparatus.

FIG. 2 is a second perspective exploded view of FIG. 1;
FIG. 3 is a third perspective exploded view of FIG. 1;
FIG. 4 is a top view of the bucket shown in FIG. 1;
FIG. 5 is a top view of the self contained plant growing apparatus thereof;
FIG. 6 is a front view thereof;
FIG. 7 is a side view thereof;
FIG. 8 is a bottom view thereof;
FIG. 9 is a rear view thereof; and,
FIG. 10 is an opposite side view of FIG. 7.**1 Claim, 4 Drawing Sheets**Fig. 3
